DOOR LATCH

Anton Diemer, Stuttgart, Germany

Original application November 13, 1939, Serial No. 303,977. Divided and this application October 10, 1940, Serial No. 360,571. In Germany May 12, 1938

6 Claims. (Cl. 292—64)

This application is a division of application Serial No. 303,977, filed November 13th, 1939.

This invention relates to door latches, especially for doors of motor vehicles and for other doors which when closed are under spring tension, the bolt of such latches carrying out, in addition to its forward motion, also a transverse one or a cross motion. An object of such double motion is to secure an easy entering of the head of the latch bolt into the striker plate or behind the locking wedge, despite the door being distorted or being under spring tension when in closed position. This should occur prior to the door being completely introduced into the body frame, so that such doors need not be slammed. However, since with latches of known structure the bolt performs both these movements simultaneously, the results aimed at are not always securely attained. This is due to the fact that especially with bolts having their forward motion depending upon spring action only it may occur that the head of the bolt will not enter sufficiently deep into the striker plate opening or behind the locking wedge, being thereon jammed in the attained position on account of great friction or pressure. In such a condition the door may open accidentally upon the occurrence of the slightest concussion or distortion.

The present invention has for its object to remove this drawback, this being achieved by a suitable connection between the door handle and the latch bolt providing for both said movements being carried out consecutively only. In this way when a latch is to be unlocked, the bolt performs at first a cross motion only, whilst it is retracted into the latch casing after said cross motion is terminated. In locking operation, on the contrary, the bolt executes first its forward motion, whereafter when this latter is terminated, it carries out its cross motion providing for a complementary drawing of the door into the door frame.

Another object of the invention is to provide a slider between the latch bolt and a lever operated by the door handle, said slider being adapted to bear both on the latch bolt and on the latch casing through antifriction means. When the door handle performs an unlocking movement said slider first slides relative to a wedge surface whereafter it causes the latch bolt to perform its inward movement. The just mentioned wedge surface may be arranged either on the bolt or on the door casing or on the slider proper.

Other features and objects of the invention

will more fully appear from the following description of several exemplary embodiments thereof with reference to the appended drawing.

In the drawing:

Figure 1 illustrates in elevation a door lock constructed in accordance with this invention and applicable to motor vehicles one wall thereof being removed.

Figure 2 is a cross-section on the line 2—2 of Fig. 1.

Figure 3 is a cross-sectional view similar to Fig. 2 but showing a modification.

In the form illustrated in Figs. 1 and 2 the latch bolt 30 is guided slidably between walls 31 and 32 of the latch casing. The bolt proper consists of a head 34 biased towards the base plate 33 of the latch casing, of a cylindrical part 36 shiftable in a chamber of said casing and of two arms 37, 38 connecting the said cylindrical part with the bolt head. Guided in grooves 40, 41 of the walls 31 and 32 respectively is a pin 39 projecting upwardly and downwardly from the cylindrical part 36. In this way the latch bolt 30 is adapted to be moved not only in its longitudinal direction but also in a direction transverse to the plane of the latch when oscillated about the pin 39. A leaf spring 43 attached to a partition 42 of the latch casing tends steadily to urge the head 34 of the latch bolt towards the base plate 33 of the latch casing, whilst a coiled spring 44 which bears by one of its ends, at 45, against the cross wall 46 of the latch casing and by its other end, at 47, against the cylindrical part 36 of the latch bolt is adapted steadily to urge said latch bolt 30 outwardly in the direction of its length.

The latch casing is mounted in a door 49 of a motor vehicle in a known manner by means of screws 48. When the door is closed, its inner edge is applied, also in a manner known per se, under a relatively great pressure onto a yieldable sealing strip 50 provided on the rigid motor vehicle body frame 51 surrounding the door opening. The head 34 of the latch bolt bears under a suitable pressure onto the rear face of a locking wedge 52 also arranged on the frame.

A slider 55 guided by its lateral lugs 54 in a slot 53 of the casing base plate 33 is adapted to develop a pressure necessary for the closing of the door. Said slide carries on its bifurcated outer end 56 a roller 136 rotatable on a pin 57. Said roller bears, in closed position of the door, on the cambered surface 71 of the latch bolt head 34. A second roller 135 bears upon a suitable abutment such as the base plate 33 and

serves to eliminate sliding friction of the slider upon the base plate.

A cylindrically shaped end 60 of a lever 61 is engaged in a cavity 59 of the slider 55. Said lever passes downwardly between the arm 38 of the latch bolt and the casing base plate 33, its other end being fixed on a tumbler 62 journalled both in the said casing base plate and in the cover plate 63 of the latch casing.

A longitudinal bore of square cross-section is formed in the tumbler wherein a square-shaped shank 64 is inserted having attached to both its ends respectively the outer and the inner door handles 65 and 66. A contraction spring 67 having one of its ends attached to a hook-shaped extension 68 of lever 61 and connected by its other end to a pin 69 fixed in the latch casing is adapted to prevent any rattling of the upper cylinder-shaped end 60 of lever 61 in the cavity 59 of the slider 55.

When the door is firmly closed as shown in the drawing, lever 61 takes the position shown in Fig. 1. The roller 136 of slider 55 presses the latch bolt head 34 against the abutment 70 of locking wedge 52 and the roller 135 transfers the reaction force to the base plate 33 of the latch and thereby the entire door is pressed against the yieldable sealing strip 50 of the door frame. In this way the door is closed tightly and secured against rattling, being simultaneously pressed onto the edges of the said door opening. The cambered conformation of the latch bolt head 34 is such that the roller 136, when in locking position, lies upon a surface nearly parallel to the base plate 33 so that the latch device has non-reversing effect. In other words, no forces acting in longitudinal direction of the latch bolt may be created by a pressure acting transversely to the plane of the door, i. e. no forces acting both on the latch bolt proper and on the slider may be created thereby.

When the lever 61 is swung by depressing the outer or inner door handle 65 or 66, it first withdraws roller 136 from the surface 71 permitting spring 43 to swing the latch inwardly and thereafter the cylindrical head 60 of the slider 55 shifts the latch bolt in its longitudinal direction until it clears the keeper 52. The door may be now entirely opened.

When a closing movement of the door is carried out the above recited operative steps follow in opposite order. So when one of the door handles 65, 66 has been depressed, the door is primarily closed so far only that its inner surface 72 bears but slightly on the yielding sealing strip 50. By moving the door handle upwards, the bolt is shifted out of the latch casing until it takes a position behind keeper 52. Such outward motion of the bolt is assisted by springs 44 and 67. Should now the lever 61 be brought back into the position of Fig. 1 by a further upward movement of the door handle, it will move the slider by means of its cylindrical head 60 in outward direction, whereas the latch bolt 30 is no longer moving outwardly for the reason that its guiding pin 39 has been already brought to contact with the outer end of the guiding slots 40, 41. Therefore the roller 136 of the slider now moves along the surface 71 of the bolt head 34 and at the same time it turns the latch bolt 30 about the pin 39 up to the moment when the bolt reaches again its closing position represented on Fig. 2.

The locking operation may be also carried out without acting on the door handle by merely slamming the door. In the latter case the latch

acts as any conventional door latch wherein the bolt 30 is retracted into the latch casing when its head 34 strikes on the inclined surface 75 of the locking wedge in opposition to spring 44. Thereby neither the slider 55 nor the door handles 65, 66 change their position. As soon as the inner surface of the door gets in contact with the sealing strip 50 and said latter is sufficiently compressed by the momentum of the slammed door, the bolt head 34 snaps behind the abutment 70 of the locking wedge under the action of spring 44 whereon the door is securely latched.

It is naturally an object of this invention to have doors closed noiselessly by operating a door handle. However an additional advantage of this my invention, as it will be seen from a further description of its embodiments, resides therein that doors provided with latches made on the basis of this invention may be also closed in 10 the way heretofore practicable, where such operation would not be troublesome.

Fig. 3 illustrates a modified embodiment of the invention wherein a number of rollers 137, 138 of different diameter are arranged on a common 15 axle 139 carried by the slider 55. The rollers 138 of smaller diameter roll on the cambered surface 71 only of the latch bolt head 34, while the rollers 137 of greater diameter contact only with the base plate 33 of the latch casing. For this 20 purpose there is provided in the inclined surface 71 a depression 140 having its breadth and depth corresponding to the roller 137 having a greater diameter. By this means also sliding friction between the rollers on the one hand the base plate 35 of the latch casing or the inclined surface of the head bolt on the other hand is avoided.

Having described several illustrative embodiments of the invention it is pointed out that various changes and modifications therein may be made without departing from the invention, it being intended that the patent shall cover, by suitable expression in the appended claims, all features of patentable novelty existing in the invention disclosed, as illustrated by the embodiments described.

I claim:

1. A door latch of the kind described, comprising a casing adapted to be secured in a door, a latch bolt mounted slidably and swingably in said casing, a slider shiftably guided in said casing and adapted to be moved between a wall thereof and said latch bolt in parallelism to the sliding movement of said latch bolt, a swinging lever movably connected to said slider and being directly or indirectly attached to rotary tumbler means having door handles operatively connected therewith, spring means secured in the said lock casing being adapted to urge said bolt into its locking position, there being provided on said slider a number of rollers mutually displaced in such a way that one of said rollers engages with a base plate only of said casing, whilst another one is in engagement with an inclined surface arranged on said door latch only.

2. A door latch of the kind described, comprising a casing adapted to be secured in a door, a latch bolt mounted slidably and swingably in said casing, a slider shiftably guided in said casing and adapted to be moved between a wall thereof and said latch bolt in parallelism to the sliding movement of said latch bolt, a swinging lever movably connected to said slider and being directly or indirectly attached to rotary tumbler means having door handles operatively connected therewith, spring means secured in the said lock

casing being adapted to urge said bolt into its locking position, there being provided on the outer end of said slider a number of rollers of different diameter mounted on a common pin axle, whereby either the base plate of said latch casing or the inclined surface of said latch bolt has a depression in a place opposing the rollers of maximum diameter and being of such depth that said rollers are bearing either on the latch bolt alone or only on the base plate of said latch casing.

3. A door latch of the kind described, comprising a casing adapted to be secured in a door, a latch bolt mounted slidably and swingably in said casing, a slider shiftably guided in said casing and adapted to be moved between a wall thereof and said latch bolt, spring means secured in the said lock casing being adapted to urge said bolt into its locking position, manually operated means for operating said slider, there being provided on said slider a number of rollers mutually displaced in such a way that one of said rollers engages with a base plate only of said casing, whilst another one is in engagement with an inclined surface arranged on said door latch only.

4. A door latch of the kind described, comprising a casing adapted to be secured in a door, a latch bolt mounted slidably and swingably in said casing, a slider shiftably guided in said casing and adapted to be moved between a wall thereof and said latch bolt, spring means secured in the said lock casing being adapted to urge said bolt into its locking position, manual means for operating said slider, an abutment, said bolt and said abutment having surfaces converging in the direction of the bolt locking position, a plurality of rollers on said slider mutually displaced in such a way that one of said rollers engages only

with said abutment, whilst another one is in engagement with said door latch only.

5. A door latch of the kind described, comprising a casing adapted to be secured in a door, a latch bolt mounted slidably and swingably in said casing, a slider shiftably guided in said casing and adapted to be moved between a wall thereof and said latch bolt, spring means secured in the said lock casing being adapted to urge said bolt into its locking position, manual means for operating said slider, an abutment, said bolt and said abutment having surfaces converging in the direction of the bolt locking position, a plurality of rollers of different diameter mounted on said slider on a common axle, one of said converging surfaces having a depression opposite the rollers of maximum diameter and being of such depth that said rollers bear either on the latch bolt alone or only on said abutment.

20 6. A door latch of the kind described comprising a casing adapted to be secured in a door said casing being formed with an inwardly facing surface, a latch bolt mounted slidably and swingably in said casing, said bolt being formed with a surface facing said surface on the casing, a slider shiftably guided in said casing and adapted to be moved between a wall thereof and said latch bolt, spring means secured in the said lock casing being adapted to urge said bolt into its locking position, manually operated means for operating said slider, there being provided on the outer end of said slider a number of rollers of different diameter mounted on a common axis, each adapted for engaging one of said surfaces, one of said surfaces having depressions opposite the rollers of maximum diameter which are of such depth that some of said rollers bear on the latch bolt alone and the others only on the base plate of said latch casing.

ANTON DIEMER.
